UNITED STATES PATENT OFFICE.

OLIVER HOLDSWORTH, OF OAKLAND, CALIFORNIA.

WINDOW-SASH LOCK.

1,345,928.

Specification of Letters Patent.

Patented July 6, 1920.

Application filed January 16, 1920. Serial No. 351,904.

To all whom it may concern:

Be it known that I, OLIVER HOLDSWORTH, a citizen of the United States, residing at Oakland, in the county of Alameda and the 5 State of California, have invented a new and useful Window-Sash Lock, of which the following is a specification.

My invention relates to improvements in window sash locks and the object of my 10 improvement is, to afford facilities for preventing the opening of the sashes beyond a given distance.

I attain this object by the mechanism 15 illustrated in the accompanying drawing in which the numerals refer to the several parts throughout the view.

The plate, 1, its upper and lower brackets, 2 and 3, to which is attached perpendicular front and back guide rods 4 and 5, and provided 20 with an aperture in upper and a pocket in lower bracket for the reception of tubes referred to hereinafter, constitute the framework of the window sash lock, which is secured by screws to the face of stile of 25 upper sash.

The front guide rod 4, being attached by a threaded end to bracket 2, and extending part way down toward bracket 3, the back 30 guide rod 5, secured in the same manner to bracket 3, and extending upward into center of aperture provided in bracket 2, a slide bar 6, to which, into and through is attached the lower end of a tube 7, that is slidably 35 mounted over back guide rod 5, and adapted to slide back and forth through aperture in bracket 2, during operation of slide bar 6, a tube 8, pointed at lower end and provided with a rim at upper end slidably mounted over front guide rod 4, lower or pointed end 40 adapted to pass though an opening provided in slide bar 6, and into the pocket in bracket 3, thereby holding slide bar 6, in an operating position overlapping top rail of lower sash.

Upon the opening of either of the sashes, slide bar 6, adapted to and carrying tube 8, by its top rim and sliding tube 7, through aperture in bracket 2, is moved by top rail

of lower sash upward under and is stopped by bracket 2, preventing the further opening 50 of the sashes, the slide bar 6, and tubes 7 and 8, dropping to their former positions upon the closing of the same.

When the sashes are in a closed position, the tube 8, may be raised out of the pocket in 55 bracket 3 and through the opening in slide bar 6, allowing slide bar 6, attached to back tube 7, to be turned on guide rod 5, out of path of top rail of lower sash, allowing full movement of the sashes.

I am aware that, prior to my invention, window sash locks have been made to swing out and into path of ascending sash and supported by bracket plates. I therefore do not claim such a combination broadly, but 65

I claim:

A window sash lock of the character described, in combination with a pair of vertical sliding sashes comprising a plate, adapted to be attached to the stile of the upper sash, 70 said plate having upper and lower brackets adapted to and carrying back and front guide rods, front and back tubes slidably mounted on said guide rods, said upper bracket having an aperture and said lower 75 bracket having a pocket for the reception of the said front and back tubes, the said tubes operating in conjunction with a projecting and retractable slide bar which is attached to the lower end of said back tube and provided 80 with an opening for engagement with said front tube; said front tube being pointed at its lower end and provided with a rim at its upper end, is slidably mounted through an opening in said slide bar, the 85 lower pointed end being adapted to drop into said pocket in the lower of said brackets, holding the said slide bar in a locked and operating position overlapping the top rail of the lower sash, whereby upon 90 the movement of either of the sashes, said slide bar carrying the said front tube by its top rim is forced upward under and is stopped by said upper bracket, thereby limiting the relative movement of the sashes.

OLIVER HOLDSWORTH.
